J. A. HOWE,
INSTRUMENT HOUSING SUPPORT,
APPLICATION FILED FEB. 24, 1916.

1,272,448.

Patented July 16, 1918.

UNITED STATES PATENT OFFICE

JAMES A. HOWE, OF ROCHESTER, NEW YORK, ASSIGNOR TO TAYLOR INSTRUMENT COMPANIES, OF ROCHESTER, NEW YORK, A CORPORATION OF NEW YORK.

INSTRUMENT-HOUSING SUPPORT.

1,272,448.

Specification of Letters Patent.

Patented July 16, 1918.

Application filed February 24, 1916. Serial No. 80,281.

To all whom it may concern:

Be it known that I, JAMES A. HOWE, of Rochester, in the county of Monroe and State of New York, have invented certain new and useful Improvements in Instrument-Housing Supports; and I do hereby declare the following to be a full, clear, and exact description of the same, reference being had to the accompanying drawings, 10 forming a part of this specification, and to the reference-numerals marked thereon.

My invention has to do with housings or casings such as are used to receive the working parts of small clocks, barometers and 15 similar mechanisms, and it has for its object the provision of adjustable supports or legs that can be employed when the device is to be rested on a table or horizontal support and which can be folded out of the way and 20 within the housing, so as not to detract from the appearance of the latter, when it is suspended from a wall or vertical support. More particularly, the invention resides in a 25 readily adjustable construction that can be applied to a housing of the general character mentioned at no great additional cost, affording an arrangement that permits of folding the supports out of the way, within 30 the housing, when the structure is suspended, at the same time making it possible to easily move the supporting legs into operative position when desirable to rest the instrument on a table or other base. To these and other ends the invention consists 35 in certain improvements and combinations of parts all as will be hereinafter more fully described, the novel features being pointed out in the claims at the end of the specification.

40 In the drawings:

Figure 1 is a rear elevation of a barometer housing showing the application of my improvements to the same;

Fig. 2 is a side elevation;

45 Fig. 3 is a bottom plan view;

Fig. 4 is a sectional view on line 4^a—4^a of Fig. 3, and

Fig. 5 is a sectional view on line 5^a—5^a of Fig. 1.

50 Similar reference characters throughout the several views indicate the same parts.

The invention may be adapted in practical form in a variety of ways, while having in view the general purpose to be attained and in the present embodiment I have

shown by way of illustration, a barometer casing, this being an instrument that is frequently located on a wall or other vertical support from which it is suspended, while in some instances it is desirable to arrange it 60 on a table or similar horizontal support, under which conditions it is necessary to provide supporting legs, since in the vast majority of these structures the housing is generally of annular formation.

In the structure disclosed, the housing comprises a back or rear wall 1 which is circular and connected to an annular portion including a bottom wall 2 which presents a cylindrical outer surface and is provided 70 with a slot or opening terminating at the points designated by 3 as shown in Fig. 4. Adjustably arranged within the housing are the supporting legs which are movable through the opening in the bottom wall of 75 the housing into and out of operative position, and adapted to be retained substantially within the housing when not in use. With this general purpose in view, I employ a pair of supporting legs, each of which 80 is designated generally by 4 and is pivoted on a bearing 5 secured to the rear wall 1. The legs 4 are movable within the slot or opening aforementioned, which latter is preferably arranged adjacent to the rear 85 wall as shown clearly in Fig. 5, and this arrangement provides a very strong and efficient, while at the same time economical structure, although other arrangements might be had which would more or less successfully carry out the underlying purpose 90 of my improvement. The outer edge of each of the supporting legs 4 is curved as shown at 6 to conform to the curvature of the bottom wall of the housing when the supporting leg is out of operative position in the manner shown in Fig. 4, thereby affording to all intents and purposes, a continuation 95 of the housing, presenting a pleasing appearance and also preventing access of dust and moisture to the interior of the housing. It is also desirable that the slot or opening in the housing be practically filled when the supporting legs are not in use and for the carrying out of this feature of the invention, the 100 supporting legs 4 are each provided with a tail piece or rear extension 7 which projects to the end of the slot or opening when the supporting leg is out of use as indicated in Fig. 4, and in the form shown, the support- 110

ing legs are extended toward each other sufficiently to bring their adjacent ends into juxtaposition when swung inwardly in the manner shown in Fig. 4. Outward movement of the supporting legs is limited by their outer edges 6 coming into engagement with the ends of the slot as shown in Fig. 1, while their inward movement is limited by projections or lugs 8 which engage the outer surface of the bottom wall at a point adjacent to the slot or opening in the manner shown in Fig. 3. The lugs 8 also serve as a means for engaging the supporting legs in order to move them to their operative or outer positions.

9 is a ring or loop for suspending the housing on a wall or vertical support, in which event the supporting legs are adjusted inwardly of the housing within the slot or opening to the position shown in Figs. 3 and 4, entirely closing the opening and affording an unobstructed exterior for the curved bottom wall of the housing. When the device is to be supported on a table or horizontal base, the supporting legs are grasped by means of the lugs or projections 8 and pulled outwardly to the limit of their outward movements, assuming the position shown in Figs. 1 and 2 and thereby affording means for supporting the housing at two

points in addition to the bottom of the housing, so that the structure is maintained in the proper vertical position upon the table.

I claim as my invention:

1. In a housing for a barometer or the like, the combination with a rear wall of substantially circular form, a substantially cylindrical bottom wall secured to the outer edge of the rear wall and provided with a slot, a pair of supporting legs pivoted to said rear wall and extending into said slot and closing the same substantially flush with the outer surface of said bottom wall, and means for withdrawing the legs against the outer ends of the slot to support the casing. 45

2. In a housing for a barometer or the like, the combination with a rear wall of substantially circular form, a substantially cylindrical bottom wall secured to the outer edge of the rear wall and provided with a 50 slot adjacent the said rear wall, a pair of supporting legs pivoted to the rear wall and adapted to substantially close the slot when in retracted position, and means for withdrawing the legs against the ends of the slot 55 to support the casing.

JAMES A. HOWE.
